[57] **CLAIM**

The ornamental design for a toy storage and display box, as shown and described.

DESCRIPTION

FIG. 1 is a front elevational view of a toy storage and display box illustrating my new design;

FIG. 2 is a side view thereof, the opposite side being a mirror image thereof;

FIG. 3 is a front elevational view thereof with the removable front cover panel removed for clarity of illustration;

FIG. 4 is a rear elevational view thereof;

FIG. 5 is a top plan view of FIG. 3;

FIG. 6 is a bottom plan view thereof;

FIG. 7 is a front elevational view of FIG. 3 in unfolded condition with the outer hardware removed for convenience of illustration and shown on a slightly reduced scale; and,

FIG. 8 is a perspective view of FIG. 7 on a reduced scale.
